UNITED STATES PATENT OFFICE.

ROBERT THOMSON, OF POLLOKSHIELDS, GLASGOW, SCOTLAND.

PILE, PIER, WHARF, AND LIKE STRUCTURE.

1,081,171.

Specification of Letters Patent.

Patented Dec. 9, 1913.

Application filed January 15, 1912. Serial No. 671,162.

To all whom it may concern:

Be it known that I, ROBERT THOMSON, a subject of the King of Great Britain and Ireland, and a resident of Pollokshields, Glasgow, Scotland, have invented certain new and useful Improvements in Piles, Piérs, Wharves, and like Structures, of which the following is the specification.

The invention has for its object to provide 10 a pile or pier of improved form and construction for use in wharves, bridges, and like structures.

A pile or pier made according to the invention has about its lower part—that is to say, at or below the surface level of the ground when the pile has been driven—a laterally projecting member of crinoline or inverted bowl form. The lower part of the pile is of usual comparatively small sectional 15 area convenient for driving; and the upper part above the laterally projecting member may be of increased sectional area to form a pier offering adequate lateral resistance in 20 structures such as wharves. The whole is preferably constructed of metal and concrete reinforcing one another—the pile proper having a metallic core either hollow or solid incased in a concrete shaft; and it may be reinforced after the manner described in the 25 specification of the application for a patent Serial No. 654336 Oct. 12, 1911, while the pier part, if there be one, is preferably similarly reinforced and also the laterally projecting member.

30 The improved form of pile or pier may be used in conjunction with floors of the type described in the specification of the application for a patent Serial No. 654335 Oct. 1911.

40 In order that the invention and the manner of performing the same may be properly understood, there is hereunto appended a sheet of explanatory drawings illustrative of an example of the carrying out of the invention, Figure 1 being a skeleton side elevation, Fig. 2 a like plan, and Fig. 3 a sectional side elevation.

45 In this example—merely illustrative and in nowise limitative—the pile part, 5, of concrete, reinforced after the manner described in the first specification hereinbefore referred to, has an axial metal core, 6, which may be hollow or solid. The lateral and inverted bowl-like member, 7, has a cutting edge, 8, and is reinforced by rings, 9, radial curved rods, 10, and, further, by radial webs,

11, within which are embedded rods 12, the ends of which are bent and hooked over the rings, 9. When a pier-like part is applied above the member, 7, it takes the form indicated by chain lines, 13, and is preferably of that reinforced construction before referred to. Apertures, 14, are preferably provided in the member, 7, for a purpose hereinafter set forth.

It is here to be pointed out that the primary essence of the invention lies in the form of the pile and not in its construction—that, while forming part of the invention, is secondary—and any materials or combination thereof may be employed.

In erecting the pile it may be driven in the ordinary way, with or without the assistance of water jets delivered through a hollow axial core, or it may be sunk by the joint action of gravity due to its own weight with the assistance of either or both a water jet and a suction nozzle. Or it may be seated by the action of water jets alone, or by suction alone. The sand and other matters dislodged by the jets from under the inverted bowl-like member, 7, are discharged through the apertures, 14, or they may be withdrawn by suction by pipes introduced therethrough. After the pile is *in situ*, concrete or the like 55 is filled in through these apertures, forming the whole into a solid mass.

If the upper part is to form a pier, it is increased to the desired area by concrete construction reinforced after the manner set forth.

The lateral and inverted bowl-like member may be made separately from the pile portion and be afterward slipped over or be carried partly on the top of that portion 95 and partly on the ground and concrete filling.

Very conveniently the improved pile or pier may be employed in combination with floor structures of the type set forth in the specification last hereinbefore referred to, 100 the anchorage devices of that type of floor being, of course, received by the upper ends of the piles or piers.

What I claim is:—

1. A reinforced concrete structure comprising a pile having a central metallic core, a concrete casing therefor, and spaced above the entering end of the pile and attached thereto an inverted bowl-like member adapted to rest substantially at ground level, as 110 described.

2. A reinforced concrete structure com-

prising a pile having a central metallic core, a concrete casing therefor, and spaced above the entering end of the pile and attached thereto an inverted bowl-like member adapted to rest substantially at ground level, said bowl-like member being apertured to admit concrete after the pile is in position.

3. A reinforced concrete structure comprising a pile having a central metallic core, a concrete casing therefor, and spaced above the entering end of the pile and attached thereto an inverted bowl-like member adapted to rest substantially at ground level, said bowl-like member being apertured to admit concrete after the pile is in position, together with pier-forming concrete material surrounding said pile above and resting on said bowl-like member, substantially as described.

20 4. In a pile or pier for use in wharves, bridges, and like structures; a pile or pier part of reinforced concrete, an axial metallic core therein, a lateral inverted bowl-like projection of concrete thereon, metal rings and curved radially disposed rods in the body of the bowl-like part, radial webs

within that part and curved hook-ended rods in the webs the hook ends of which engage the rings.

5. A reinforced concrete pile, having a hollow metallic core with concrete casing, and spaced above the lower end thereof and attached thereto an inverted bowl-like base of reinforced concrete, together with a concrete pier body surrounding the core above said bowl-like base only, substantially as described.

6. A reinforced concrete pile having a hollow metallic core, with concrete casing and spaced above the lower end thereof and attached thereto an inverted bowl-like base of reinforced concrete, together with a concrete pier body surrounding the core above the bowl-like base only, said base being apertured for the purpose described.

In testimony whereof I have signed my name to this specification, in the presence of two subscribing witnesses.

ROBERT THOMSON.
